UNITED STATES PATENT OFFICE.

ALBERT H. RIEMER, OF MILWAUKEE, WISCONSIN.

SHOE.

SPECIFICATION forming part of Letters Patent No. 621,287, dated March 14, 1899.

Application filed December 13, 1897. Serial No. 661,649. (No model.)

To all whom it may concern:

Be it known that I, ALBERT H. RIEMER, a citizen of the United States, residing at Milwaukee, in the county of Milwaukee and State 5 of Wisconsin, have invented new and useful Improvements in Shoes, of which the following is a specification.

My invention relates to improvements in that class of shoes which are provided with 10 wooden soles, and pertains more especially to the device by which the upper of the shoe is secured to the sole.

The construction of my shoe is explained by reference to the accompanying drawings, 15 in which—

Figure 1 represents a side view. Fig. 2 is a vertical section drawn on line X X of Fig. 1, and Fig. 3 is a central vertical section view.

Like parts are referred to by the same reference-letters.

A represents the sole of the shoe, which is provided with a V-shaped groove B, made for the reception of the lower edge of the upper of the shoe C, which is secured therein by the 25 fastening-wire D and wire-retaining staples E. As indicated in Figs. 2 and 3, the lower edge of the upper is drawn firmly downward within the groove B by the retaining-wire D, having its edge protruding outwardly flush 30 with the outer edge of the sole, as indicated at F. When the wire has been drawn, as indicated, firmly around the lower edge of the upper, the same is secured in place by the series of staples E, which engage around the 35 wire and are firmly driven over the same into the sole, whereby the upper is secured firmly in place. The heel or rear part of the shoe is provided with a stiffening-counter G, which is stitched to the upper in the ordinary manner, as indicated at H, and its lower edge is 40 drawn down firmly into the V-shaped groove

B, where it is secured in place between the upper of the shoe and the interior bearing-surface of the sole, as indicated in Fig. 3. It is obvious that by the device described the 45 leather is held in the groove of the sole by the binding-wire, while the binding-wire is in turn held against the leather and made to conform to the concave or inward curves of the upper-retaining groove around the edge of the sole 50 by the staples, which staples straddle said binding-wire and are driven through the edge of the upper into the sole, thereby drawing said binding-wire down firmly against the exterior surface of the leather. When the upper 55 has been thus secured to the sole, the outward projecting edge may be nicely trimmed off flush with the edge of the sole, which gives the shoe a neat and finished appearance.

Having thus described my invention, what 60 I claim as new, and desire to secure by Letters Patent, is—

In a shoe, the device for securing a leather upper to a wooden sole, consisting in the combination of a sole A, provided with a V-shaped 65 groove B, upper C, upper-retaining binding-wire D, and wire-retaining staples E, said upper being drawn down and firmly held within said groove by said binding-wire D, while said binding-wire is in turn drawn down 70 against said upper by said retaining-staples, which staples straddle or engage around said binding-wire, and are driven through the upper into the wooden sole, substantially as and for the purpose specified. 75

In testimony whereof I affix my signature in the presence of two witnesses.

ALBERT H. RIEMER.
